THEODORE A. SCHAFER, OF BROOKLYN, NEW YORK, ASSIGNOR TO INTERSTATE
ELASTIC BRAID COMPANY, OF BROOKLYN, NEW YORK, A CORPORATION OF
NEW YORK.

CLASP FOR ARMBANDS AND THE LIKE.

1,300,198.

Specification of Letters Patent.

Patented Apr. 8, 1919.

Application filed May 2, 1918. Serial No. 232,008.

To all whom it may concern:

Be it known that I, THEODORE A. SCHAFER, a citizen of Russia, residing at Brooklyn, New York, have invented a new and useful Clasp for Armbands and the like, of which the following is a specification.

My invention relates to arm bands and the like. My object is to provide a new and ornamental clip for holding an ornamental bow in place or for covering the joined ends of the elastic band proper.

In the drawing:

Figure 1, is a perspective view of a strip from which short lengths are cut for the individual clips.

Fig. 2, is a similar view of the finished arm band.

Fig. 3, is an enlarged sectional view of the clip before it is bent down into the final holding position.

Fig. 4, is a similar view of the clip when bent down in the final holding position.

Fig. 5, is a diagrammatic view of a modification.

1 represents an elastic band. 2 represents an ornamental bow which is applied over the point or junction of the ends of the band 1, which ends may be initially joined in any desired manner and by any suitable means.

30 In order to hold the bow in place and at the same time to hide the joined ends of the elastic band I provide a clip which comprises a core 3 of comparatively thin sheet metal upon which has been braided, so as to com-

35 pletely envelop the same, a fabric covering 4 preferably of silk or the like. By braiding the covering on the core the latter is completely enveloped by a seamless flat fabric tube. If desired, the fabric covering may

40 be cemented to the core by any suitable adhesive which may be applied to the core either while the braiding operation is going on or at any time. In making the material for the clips I first form it as a long strip

45 (see Fig. 1) and thereafter I cut off from the strip short pieces of the desired length. By providing the tubular covering on the metal core, the former will be securely and permanently applied and both surfaces of the clip

50 will have a corresponding finish. By providing cement, the ends of the fabric covering are safeguarded against fraying when the long strip is cut into short lengths to form separate clips. Instead of covering the

entire core 3 with cement, it may be desired 55 to merely dip the ends of the individual clips in cement when the same are severed off from the long strip, the only function of the cement being to prevent the fraying of the ends of the fabric covering. Even this is 60 not essential in every instance, since the ends of the clips may be united in such a manner as to prevent said fraying, for example, I have diagrammatically shown in Fig. 5, a method of interlocking the ends of the clip 65 in such a manner as to prevent fraying, as I will later describe. When the clip is to be applied it is first bent into the form shown in Fig. 3. It is next slipped over the bow and the joined ends of the arm band and 70 then the ends of the clip are bent in as shown in Figs. 4 and 5, the extreme ends being preferably bent in as shown so that the metal ends will not press against the body of the wearer or an underlying garment. 75

In Fig. 5 I have shown the two extreme ends of the clip as being hooked in opposite directions, the two hooks interengaging and then being clamped tightly together thus binding the ends of the fabric covering in 80 the final clenching operation so that they will not fray. Since both sides of each clip correspond, owing to the seamless character of the fabric covering, it is immaterial which way the clip is bent in the act of applying 85 it. This is a feature of great advantage in that much time is saved in the manufacture of the articles. Furthermore the finished article is more durable since there are no seams to open up or become loose. Again by 90 braiding the covering on the core a very handsome and ornamental effect is produced.

What I claim is:—

As an article of manufacture, an arm band 95 formed of a strip of elastic material, with means for joining the ends together to form a permanently closed band, a clip covering and protecting said means, said clip comprising a core of metal and a seamless tubular fabric covering braided thereon whereby either face of said clip may be applied to and bent around said means for permanently connecting the ends of the elastic strip, the ends of said clip being located at the inner 100 side of said arm band. 105
